[57] CLAIM

The ornamental design for a golf ball tee, as shown and described.

DESCRIPTION

FIG. 1 is a perspective view of a golf ball tee embodying our new design;

FIG. 2 is a side elevational view thereof, the three sides of the golf ball tee being the same except for the attached tag;

FIG. 3 is a top plan view thereof; and,

FIG. 4 is a bottom view thereof.

FIG. 1

FIG. 3

FIG. 2

FIG. 4
